UNITED STATES PATENT OFFICE.

GEORGE LIVINGSTON RICHARDS, OF LONDON, ENGLAND, ASSIGNOR TO INTERNATIONAL STAMP AND TICKET MACHINE COMPANY, OF KITTERY, MAINE.

MACHINE FOR DELIVERING POSTAGE-STAMPS, TICKETS, AND THE LIKE.

1,114,912.

Specification of Letters Patent.

Patented Oct. 27, 1914.

Application filed August 25, 1913. Serial No. 736,560.

To all whom it may concern:

Be it known that I, GEORGE LIVINGSTON RICHARDS, a citizen of the United States of America, residing at London, in England, have invented certain new and useful Improvements Relating to Machines for Delivering Postage-Stamps, Tickets, and the like, of which the following is a specification.

This invention relates to machines for delivering postage stamps, tickets and the like more particularly in strip form, for example, from a storage reel or the like, which machine may be rendered operative by the action of a coin or token representing the amount tendered in payment for such articles.

The invention comprises novel means for feeding the strip of stamps, tickets or the like and for detaching one or more thereof from said strip. In machines of this class considerable difficulty has been experienced in accurately feeding the strip and in detaching the stamps or the like at the perforations or scored portions of the strip at predetermined intervals, especially when the strip is not made continuous and has been joined together at intervals, the joints being irregularly effected.

The invention broadly comprises a table on which the strip to be fed is placed, a reciprocating feed-arm at one side of said table provided with one or more sharp teeth or equivalents adapted to engage perforations or joints in the strip to feed the latter, and on the other side of said table an arm having a cutting member adapted when the feed-arm has reached the end of the table to coact with the tooth or teeth on said feed-arm to sever the strip exactly at the perforations or joint and thus detach a portion from said strip.

A practical embodiment of the invention is illustrated in the accompanying drawings, in which—

45 Figure 1 is a side elevation of the machine. Fig. 2 is an end elevation from the right hand side of Fig. 1, and Fig. 3 is a plan view.

The apparatus comprises a stationary 50 plate or table 1 upon which the strip of stamps α or portion thereof taken from a storage reel 2 and passed about a guide roll 2 a is laid in a predetermined position, the reel 2 being shown as mounted on a bracket 55 2 b extending from the base-plate 20 of the

machine. The table is longitudinally grooved as at 3, either throughout, or as shown for a portion of its length, and above said table 1, is disposed a flat slotted spring member 4, pivoted at 4 a in lateral plates 4 b extending upward at each side of the table. The strip is inserted between said table and the spring member 4 and the latter bears lightly on the strip to maintain same in intimate contact with the table 1. Above the said table 1, is disposed a reciprocating arm 5 carried by arms 5 a pivoted on a shaft 5 b mounted in a slide block 11 provided with rollers 11 a bearing on the base-plate 20 and adapted to be reciprocated on said base-plate by suitable means (not shown) applied to one or both projecting ends of said shaft 5 b . The arm 5 is provided at its forward end with a series of angularly disposed sharp teeth 6, in the construction shown these teeth being formed on a plate 6 a secured by screws 6 b to the arm and coinciding with the grooves 3, in the table 1. The teeth extend through slots with which the aforesaid spring member 4 is provided to engage the perforations or joints in the strip so that as the arm 5 moves in the forward direction (to the right of Figs. 1 and 2) it will engage said perforations or joints in the strip and feed the latter forward to the end of the table 1, the teeth 6 at the same time passing through the perforations in the strip, and extending somewhat into the grooves 3, in the table 1, thus insuring a positive feed of the strip. During the forward movement of the strip 90 the pressure of the spring member 4, is taken off the strip by a projection 17 depending from the lower surface of arm 5 engaging the curved end 29 of said spring member 4. The arm 5 is adapted to travel in a rearward (to the left) direction beyond the length of the stamp or other article to be fed so that on its forward movement it will not fail to engage the next line of perforations or joint in the strip, thus compensating for any inequalities or irregularity in said perforations or joints.

The arm 5 is lightly pressed by a spring 7 (the pressure of which is adjustable as by a set screw 7 a) toward the strip, and as the forward or feed movement progresses also presses with its projection 17 with increasing force on the tail 29 of the aforesaid flat spring member 4, thus releasing the strip of the pressure of said spring member dur- 110

ing the feed movement, the arm 5 being guided in its movements by lateral projections 8, at the forward end of the arm engaging in the forward direction under cam-plates 9, disposed at each side of the path 5 of travel of the arm on the plates 4^b before referred to. On the return movement of the arm 5 projections 8 move over the upper surfaces of the cam-plates, the arm being tilted 10 for this purpose by the spring 7 acting on an enlargement 5^c at the rear end of the arm and the forward ends of the cam-plates being curved as at 9^a to assist this action. The arm 5 is thus carried clear of the strip on 15 its return stroke.

Located below table 1, is a reciprocating arm 10, pivoted on the shaft 5^b in the slide-block 11, said arm 10, being provided at its forward end with an angularly disposed 20 knife or blade 12 which when said arm 10, has reached the end of the table 1, is caused to meet the teeth 6 of feed-arm 5, and engage or coact therewith to sever the strip exactly at the perforations or joint, the table 1, being preferably chamfered at its forward 25 edge as at 30 to assist or permit this shearing action. This movement of the arm 10, is effected through suitably shaped levers 14, loosely mounted on shaft 5^b on either 30 side and provided with a curved face at 15, which during the forward movement of the slide-block 11 engages a roller 16 mounted exteriorly one on each of the side plates 4^b, the levers engaging extensions 10^a of the 35 arm 10, and acting thereon to rock the arm about its pivot, whereby the cutting action of the knife is produced at the proper time. On the return stroke, the arms 5 and 10 are again separated, the former by moving up 40 over the cam plates 9 as described and the latter by the action of a spring 13 carried by the slide-block and acting on the arm. The levers 14 are held in their normal position in contact with the extensions of arm 45 10 by means of springs 14^a which permit the curved parts 15 thereof to trip past the rollers 16 on the return stroke.

Immediately after the strip is in position for cutting the flat spring 4 again engages 50 same by the projection 17 on arm 5 having passed over the tail 20, thus preventing movement of the strip during said cutting or during the return movement of the feed arm. Adjustment of the spring 4 is made 55 by set screws 18 at each side engaging extensions 19 of the spring 4.

A roller 21 mounted to slide vertically in bearings 22 normally bears on the strip of stamps but drops into a recess 23 in the 60 table when the last stamp or ticket has passed from under said roller. The roller coöperates with a rod 24 which normally engages a lever 25 carried by the standard 2^a, consequently when said roller drops the 65 lever 25 is released and through suitable de-

vices (not shown) actuates means by which the coin aperture is closed in a manner which will be readily understood.

I do not limit myself to the exact construction and arrangement of parts hereinbefore described and illustrated in the drawings, since the same may be varied within limits prescribed by the appended claims without departing from the spirit of the invention. In said claims the term stamps is intended 75 to include tickets and the like previously referred to.

What I claim as my invention and desire to secure by Letters Patent of the United States is:—

1. In a strip feeding and cutting machine, the combination with a fixed table over which the strip to be cut travels, of a strip feeding member on one side of said table adapted to swing toward and from the same 80 to engage the strip and to move longitudinally of the table to advance said strip thereover, a swinging cutting member on the opposite side of the table adapted to move longitudinally in unison with the feeding member, and means for causing said members to swing toward each other and coact at the end of the feeding movement to detach a portion from said strip.

2. In a strip feeding and cutting machine, 95 the combination with a fixed table over which the strip to be cut travels, of a strip feeding member on one side of said table adapted to swing toward and from the same to engage said strip and to move it 100 longitudinally of the table a definite distance, projecting teeth on said member to positively engage said strip, a swinging cutting member on the opposite side of said table adapted to move longitudinally in unison with the feeding member, and means for causing said feeding and cutting members to swing toward each other and coact at the end of the feeding movement to detach a portion from said strip.

3. In a machine for delivering stamps, the combination of a support to receive a strip of stamps to be fed, a pivoted reciprocatory member on one side of said support having a plurality of teeth at its forward edge to engage and feed said strip along said support, a pivoted reciprocatory cutting member on the other side of said support, and means for rocking said feeding member and said cutting member toward each other at 115 the end of the feeding movement to cause them to coact and detach a stamp from said strip.

4. In a machine for delivering stamps, the combination of a table to receive a strip of stamps to be fed, a feed member at one side of said table adapted to convey the strip along same, a cutting member at the other side of said table, said members coacting at 120 the end of the table to detach a stamp from 130

the strip, resilient means adapted to normally exert pressure to hold the stamps against the table and means operated by the movement of the feed member during its feeding movement to release said pressure.

5. In a machine for delivering stamps, the combination of a table to receive a strip of stamps to be fed, a feed member at one side of said table, teeth at the outer end of said 10 member adapted to engage and feed the stamps along said table, a cutting member at the other side of said table, a blade carried by said cutting member adapted to coact with said teeth to detach a stamp from 15 the strip when said members reach one end of said table, an adjustable pivoted spring member adapted to normally bear on the stamps, and provided with slots for passage of the teeth of the feed member, a deflected tail to said spring, and a projection on the feed member adapted to engage said tail to relieve the pressure of the spring on the stamps.

6. In a machine for delivering stamps the combination of a table to receive the stamps, 25 reciprocating and oscillating feed and cutting members disposed on opposite sides of said table, and pivotally mounted about a common axle, a reciprocating slide carrying said axle, a spring acting on the feed member to force same toward the stamps, stationary cam members engaged by the feed member to produce the oscillations thereof, trip levers connected to the cutting member, fixed abutments engageable by said trip levers for oscillating said cutting member in one direction and a spring for oscillating said cutting member in the opposite direction.

10 In witness whereof I have signed this 40 specification in the presence of two witnesses.

GEORGE LIVINGSTON RICHARDS.
